UNITED STATES PATENT OFFICE.

HARRY PAULING, OF GELSENKIRCHEN, GERMANY, ASSIGNOR TO THE FIRM
OF SALPETERSÄURE-INDUSTRIE-GESELLSCHAFT, G. M. B. H., OF GELSEN-
KIRCHEN, GERMANY.

ELECTRODE.

No. 896,144.

Specification of Letters Patent.

Patented Aug. 18, 1908.

Application filed August 13, 1906. Serial No. 390,886.

To all whom it may concern:

Be it known that I, HARRY PAULING, a subject of the German Emperor, and resident of 84 Wilhelmstrasse, in Gelsenkirchen, in 5 the Kingdom of Prussia, German Empire, have invented certain new and useful Improvements in Electrodes, of which the following is a specification.

In the application of electricity to the treatment of gases containing oxygen, such as air, it has been found advantageous to use second-class conductors, such as melted or liquefied metal-oxids, as material from which to make the electrodes designed for effecting 10 the electrical discharges. The practical application of this method, however, has been found to involve certain difficulties and disadvantages. For example, if the electrodes are entirely formed of second-class 15 conductors, then currents of a high tension cannot be made use of, because the points of such electrodes rapidly vaporize under the action of such currents, or at least they drip off.

20 The present invention has for its object to overcome inconveniences of this nature.

To such end it consists, broadly, in producing the required second-class conductors at the points of the electrodes, consisting of a 25 suitable metal such as iron, by the electrical energy itself. The second-class conductors generated in this case constitute a metal-oxid, the electrodes being surrounded with a gas containing oxygen, namely the gas which 30 is to undergo the action of the discharges between them.

The metal-oxid thus formed can no more vaporize, because the electrodes themselves, owing to the well-known fact that metal is a 40 good conductor of heat, act to convey, from the points of the electrodes, the greatest part of the heat due to the action of the energy supplied to the electrodes. Such electrodes thus show the advantage possessed by electrodes made of the usual kind of metal, that is, a metal not capable of generating a second-class conductor, inasmuch as they like these allow of the application of high-tension currents, by preventing an 45 excess of heat, while at the same time they are possessed of the advantageous qualities attributed to second-class conductors.

In the practical application of the new electrodes I may proceed as follows: I bring 50 the points of the electrodes into mutual con-

tact, as is common with the usual metal electrodes, and leave them in this state until by the passage through of the current the points, become incandescent. In this state the latter oxidize owing to the oxygen contained in 60 the gas to be subjected to the action of the discharges. I then separate the electrodes so as to form such a distance between their points that the voltaic arcs generated are of the desired length, current-strength, and tension. 65

Electrodes of the nature described are found to be of high practical value in connection with processes for producing, by electrical discharges, nitric acid or nitric oxid 70 from air or another mixture of oxygen with nitrogen, inasmuch as the metal-oxid formed vaporizes in trifling quantities only, so that the pureness of the nitric acid or nitric oxid produced is not affected. Such is the case so 75 much the more as these vaporized quantities of metal-oxid are not soluble in nitric acid, so that they may be separated therefrom in any usual or desired manner.

The accompanying drawing illustrates a 80 form of construction adapted for electrodes made according to this invention, Figure 1 being a front elevation of a pair of such electrodes and Fig. 2 a section on the line A B of Fig. 1.

85 *e, e* are the electrodes and *o* denotes the melted metal oxids originated by the action of the arcs *f*. The electrodes are square in cross-section (Fig. 2) and are at their points provided with cooling ribs *k* formed integral 90 therewith or secured thereto in any other suitable manner.

The square cross-sectional shape and a horizontal position of the electrodes prevent the melted oxids from dripping off from the 95 electrodes, while the cooling ribs *k* act like the electrodes themselves to convey the heat originated by the energy supplied to the electrodes, so as to prevent the melted oxids from vaporizing.

100 It is to be understood that I do not desire to confine myself to a particular sort or composition of metal from which to make the new electrodes, but that any suitable metal may be used within the scope indicated by 105 the appended claim.

What is claimed is:

The herein described process for the treatment of gases by arc discharges, consisting in producing melted metal oxids at the points 110

of the electrodes made of a metal generating the said melted oxids by the action of the energy supplied to the electrodes used for the production of the said arcs, and in 5 maintaining such melted oxids in their liquid state by the said arcs, substantially as set forth.

In witness whereof I have hereunto signed my name this 23rd day of June 1906, in the presence of two subscribing witnesses.

HARRY PAULING.
